Inventor:

William D. Farren

UNITED STATES PATENT OFFICE.

WILLIAM D. FARREN, OF BOISE CITY, IDAHO TERRITORY.

TELEGRAPH-KEY.

SPECIFICATION forming part of Letters Patent No. 270,652, dated January 16, 1883.

Application filed September 6, 1882. (No model.)

To all whom it may concern:

Be it known that I, WILLIAM D. FARREN, of Boise City, in the county of Ada, and in the Territory of Idaho, have invented certain new and useful Improvements in Telegraph-Keys, both in the manufacture and use thereof; and I do hereby declare that the following is a full, clear, and exact description thereof, reference being had to the accompanying drawing, forming part of this specification.

My invention consists in a telegraph operating-key constructed of spring-steel or spring-brass, the base and lever of the key forming an entirety.

Heretofore in constructing telegraph-keys it has been customary to hang the key upon an axle which passed entirely through the key-body in a channel cut therein for that purpose, and to hold the key in place upon the axle by means of a set-screw working in the mass of the key and impinging upon the surface of the axle; or a plan has been followed in which the lever and base were two separate pieces of material, the lever being attached to the base at the extremity of either piece by means of a joint which extends lengthwise the entire width of the base of the key, the platinum points being midway between the knob and joint. In this latter process a movable knob is used to regulate the play of the lever. Continuous use of the knob for a short time has been found to result in a wearing away of the parts, and the insurmountable objection to the second style of key is here presented.

A key which will avoid the greatest obstacle to rapid and distinct telegraphy—a jarring of the parts—has been a desideratum since the earliest days of the art. By means of my invention as described below it is evident that a key can be made the lever and base of which shall be one homogeneous piece of metal without joint, connection, or attached spring. The action of the key as a whole will be apparent from the following description, reference being made to the accompanying drawing, showing the key with all its parts as plainly understood as it could be by different sectional presentations.

B is the base of the instrument, and A the

lever, which is of the same material as the base and a continuation of it, but narrower and bent over it at a height of about one inch, more or less. The knob end of the lever is bent downward until its lower surface is in the same plane with the base of the instrument. The surface of the knob is in the same plane with the surface of the lever.

S is the only adjusting-screw in the instrument.

P is the platinum-pointed screw with its lock-nut working on the platinum point Q below, which is in the head or top of the front binding-screw or leg.

C is the circuit-closer, attached to the base in a manner to prevent accidental opening of the circuit, being closer to the arm when closed than the circuit-closer of any previously used instrument, this advantage being secured by the peculiar construction of the key. The knob K is immovable.

D is a small screw-head governing the opening of the circuit-closer and preventing its being opened wider than would be desirable.

R is the back binding-screw or leg. It is screwed through the base before the lever has been bent over it.

It is evident that the construction of the key is easier and less expensive than that of either of the other keys partially described in this specification.

I desire to reserve the right to manufacture this key with or without legs.

What I claim as my invention, and desire to secure by Letters Patent, is—

1. A telegraph-key having the lever and base formed of a single piece of spring metal, substantially as shown and described.

2. A telegraph-key, substantially as shown and described, consisting of the base B and lever A, formed of a continuous piece of spring metal, and having the single adjusting-screw S.

In testimony that I claim the foregoing I have hereunto set my hand and seal this 29th day of June, 1882.

WM. D. FARREN. [L. S.]
